Patented Apr. 5, 1966

204,267

DENTAL SYRINGE

Richard B. Cocherell, 363 N. Spinks Canyon Road,
Duarte, Calif.

Filed Aug. 6, 1965, Ser. No. 86,487

Term of patent 14 years

(Cl. D24—1)

FIGURE 1 is a perspective view of a dental syringe showing my new design;

FIG. 2 is a side elevational view thereof, broken away for convenience of illustration only;

FIGURE 3 is a top plan view thereof.

The fragmentary hose member disclosed in broken lines is for illustrative purposes only.

I claim:

The ornamental design for a dental syringe, substantially as shown and described.
